UNITED STATES PATENT OFFICE

136,733

DESIGN FOR A TOY

Solomon M. Hall, Springfield, Ohio

Application October 6, 1943, Serial No. 111,276

Term of patent 7 years

To all whom it may concern:

Be it known that I, Solomon M. Hall, a citizen of the United States, residing at Springfield, in the county of Clark and State of Ohio, have invented a new, original, and ornamental Design for a Toy, of which the following is a specification, reference being had to the accompanying drawing, forming part thereof.

I claim:
The ornamental design for a toy, as shown.
SOLOMON M. HALL.
